COMPARTMENTALIZED SERVING TRAY OR THE LIKE

Alex G. Dunton, Jr., Richmond, Va., assignor to Reynolds
Metals Company, Richmond, Va., a corporation of
Delaware

Filed Oct. 6, 1965, Ser. No. 87,340

Term of patent 14 years

(Cl. D44—10)

FIG.1

FIG.2

FIG.3

FIG.4

FIG.5

FIG.6

FIGURE 1 is a top perspective view of a compartmentalized serving tray or the like showing my new design;

FIGURE 2 is a top view thereof;

FIGURE 3 is a front elevation view thereof;

FIGURE 4 is a rear elevation view thereof;

FIGURE 5 is a side elevation view thereof; and

FIGURE 6 is a bottom perspective view thereof.

I claim:

The ornamental design for a compartmentalized serving tray or the like, as shown.
